Primary Examiner — Steven J Czyz*(74) Attorney, Agent, or Firm* — Workman Nydegger(57) CLAIM

The ornamental design for a cabinet, as shown and described.

DESCRIPTION

FIG. 1 is a front perspective view of a cabinet showing our new design;

FIG. 2 is a front elevation view thereof;

FIG. 3 is a front elevation view thereof, showing the sliding door in an alternate position of use to the right of the cabinet;

FIG. 4 is a back elevation view thereof;

FIG. 5 is a top plan view thereof;

FIG. 6 is a bottom plan view thereof;

FIG. 7 is a right elevation view thereof; and,

FIG. 8 is a left elevation view thereof.

The broken lines depict portions of the article that form no part of the claimed design.
